UNITED STATES PATENT OFFICE.

JOHN M. PROVOOST, OF BUFFALO, NEW YORK.

TELEPHONE-CALL INDICATOR.

SPECIFICATION forming part of Letters Patent No. 276,465, dated April 24, 1883.

Application filed March 1, 1883. (No model.)

To all whom it may concern:

Be it known that I, JOHN M. PROVOOST, a citizen of the United States, residing at Buffalo, in the county of Erie and State of New York, have invented certain new and useful Improvements in Telephone-Call Indicators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention consists substantially of an arrow or indicator loosely pivoted to the front face of the telephone-casing, acting in conjunction with a lever loosely pivoted to such casing or a holding-plate, either on the inside 20 or outside surface thereof, such lever being adapted to be operated by the vibrating bell-hammer of the telephone, and provided with an angular projection working in a slot in the casing or holding-plate, and adapted to engage 25 with or disengage from a projection upon the arrow or indicator, another angular projection being located upon the lever and similarly working through a slot, by means of which projection the indicating-arrow may be quickly 30 and easily reset after having been thrown out of position in indicating a call at the telephone, all as will be more fully hereinafter described and claimed.

In the drawings, Figure 1 is a front view of 35 the telephone-casing, showing the application of my improved device. Fig. 2 is a rear view of the same. Fig. 3 is a front view of a modification. Figs. 4 and 5 are respectively rear and side detached views of my improved de- 40 vice, and Fig. 6 is a perspective view of the arrow or indicator.

Referring to the drawings, *a* is the front casing of the telephone-chamber, *a'* the bells, and *a²* the hammer, operating in the usual 45 manner in the slot *a³* to ring the bells.

In Figs. 1 and 2 I have shown my operating mechanism as applied inside of the casing, the arrow or indicator being of course upon the outside. In such Figs. 1 and 2, *b* is the arrow 50 or indicator, also shown more clearly in per-

spective in Fig. 6. This arrow is loosely pivoted, as shown, directly to the casing, and has the projection or shoulder *b'* upon its inner side.

c is the operating-lever, preferably straight, and pivoted at *c'* to the inner side of the casing, as shown in Fig. 2. Its upper end extends to or slightly beyond the hammer *a²*, which rings the bells. Its lower end is bent to form the projection *c²*, which extends outwardly through the elongated slot *d* in the casing *a*, and a short distance above such projection *c²* is another and similar projection, *c³*, which extends outwardly through slot *d'*, also in the casing *a*.

c⁴ is a keeper to limit the play of the lever *c*.

In Figs. 3, 4, and 5 I have shown a different way of attaching my improved device to the casing of the telephone, the device itself and its operation being in every respect the same as in Figs. 1 and 2. The arrow or indicator *b* and the operating-lever *c* are pivoted to the holding-plate *e*, having the attaching-lugs *e'*, by which to secure it removably to the casing *a*. Similar slots, *d* *d'*, are provided for the projections *c²* *c³* upon the operating-lever *c*.

The operation of the device is as follows: Assuming the projection *b'* upon the arrow *b* to be resting upon the projection *c²* of lever *c*, thus holding such arrow in a horizontal position, and the bell-hammer *a²* to be located at 80 the left of the top portion of the lever *c* and resting against the left-hand bell, it will be observed that as soon as the hammer *a²* commences to vibrate between the bells *a' a'* the lower part of the lever *c*, with its projection *c²*, 85 is thrown to the left, and the arrow *b* is dropped out of its horizontal position, thus serving its purpose of indicating that a call has been made during the absence of any one from the office or room in which the telephone is located. To 90 reset the arrow in its horizontal position it is only necessary to raise such arrow to its horizontal position, and at the same time push the lever *c*, by means of the projection *c³*, back until the shoulder *b'* upon the arrow *b* again rests 95 upon the projection *c²* upon the lever *c*. This can be very easily and quickly done with one hand.

I am aware that it is not novel, broadly, to arrange an indicator with a lever operated by 100

the bell-hammer of the telephone, and I do not claim such broad construction; but

What I do claim is—

The combination, with the pivoted arrow or indicator *b*, provided with the projection *b'*, of the pivoted lever *c*, having the supporting-projection *c²* and the operating-projection *c³*, working in the slots *d* and *d'*, the whole being applied to the casing of a telephone and oper-

ated by the vibration of the bell-hammer, substantially as shown and described.

In testimony whereof I have signed my name to this specification in the presence of two subscribing witnesses.

JOHN M. PROVOOST.
